(57) **CLAIM**

The ornamental design for an electronic sphygmomanometer as shown and described.

DESCRIPTION

FIG. 1 is a front, right, and top perspective view of an electronic sphygmomanometer, showing my new design;

FIG. 2 is a rear, left, and top elevation view thereof;

FIG. 3 is a rear, right, and bottom elevation view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines shown in the drawings are included for the purpose of illustrating portions of the electronic sphygmomanometer that form no part of the claimed design.

1 Claim, 9 Drawing Sheets
